UNITED STATES PATENT OFFICE.

EMANUEL AUFIERO, OF BROOKLYN, NEW YORK.

WARNING SIGNAL.

Application filed June 27, 1921. Serial No. 480,550.

To all whom it may concern:

Be it known that I, EMANUEL AUFIERO, a citizen of the United States, residing at Brooklyn, in the county of Kings, State 5 of New York, have invented certain new and useful Improvements in Warning Signals; and I do hereby declare the following to be a full, clear, and exact description of the invention, such as will enable 10 others skilled in the art to which it appertains to make and use the same.

This invention relates to warning signals of the type known as electric horns, and which are at the present time almost universally used for signal horns on automobiles.

The common type of automobile horn consists essentially of a metallic diaphragm adapted to be vibrated by a rotating serrated actuator which engages a striking pin or anvil attached to the center of the diaphragm. The diaphragm is customarily mounted across the open side of a sheet metal support or casing and the actuator is 20 mounted directly on the armature shaft of a small electric motor contained in a sheet metal casing usually supported and projecting rearwardly from the diaphragm casing. The shaft of the motor is ordinarily 25 perpendicular to the plane of the diaphragm and the motor shaft is offset somewhat from the center of the diaphragm so that the serrations projecting axially from the rim of the actuator will engage the anvil on the 30 diaphragm.

The reaction from the engagement of the actuator and anvil must be taken up by a thrust bearing at the end of the armature shaft remote from the diaphragm, and as 40 there is more or less wear in the bearing, also in the contacting faces of the actuator and anvil, it is highly desirable that this shaft bearing be adjustable, and in automobile horns of the better grade various means 45 are provided for effecting the adjustment of the actuator with respect to the diaphragm.

For expensive, high grade machinery, satisfactory adjustable thrust bearings are 50 now available, but for apparatus which must be sold within the price limits of an electric motor horn it has heretofore been difficult to provide a satisfactory structure in which the necessarily accurate, and at same time 55 easy, adjustment may be accomplished.

It is the object of the present invention

to provide a motor structure for electric horns of this character wherein the armature shaft is supported for adjustment as a whole relatively to the motor frame by a 60 simple, inexpensive device, adding but little to the cost of the horn, by means of which the armature shaft may be positively adjusted in both directions to take up the wear of the contacting actuator and anvil. 65

A further object of the invention is to provide a device of this kind wherein, in addition to the above mentioned adjustment, the shaft bearings themselves may be relatively adjustable to take up wear in 70 the bearings.

A further object of the invention is to provide a device of this kind which is particularly adaptable for use in connection with the electric motor construction shown 75 in my prior Patent No. 1,414,612, granted May 2, 1922.

In the accompanying drawings I have illustrated a preferred embodiment of my improved horn, and in said drawings, 80

Figure 1 is a vertical sectional view of the horn; and

Fig. 2 is a plan view of the horn casing shown in section.

Referring to the drawings, 1 indicates 85 the diaphragm casing across the open face of which the diaphragm 2 is supported, the diaphragm being clamped within the flange of the casing by means of the cover plate 3 carrying the usual projector 4. 90

The motor frame 5 is attached to the rear wall of the diaphragm casing 1 by means of suitable screws passing through the diaphragm casing, the front end piece of the frame and the inturned ends of the rear rectangular portion of the frame, and the armature shaft 6 is mounted for rotation in the end walls of the frame, the shaft projecting at its forward end through the frame and diaphragm casing to receive the actuator 7. 100 The actuator is threaded on the reduced end of the shaft 6 and is positioned for its teeth to engage the anvil 8 of the diaphragm.

The end of the shaft 6 projects through the actuator 7 and at its end is ground to 105 provide a bearing point which is engaged by a bearing cup 9 supported at the end of the depending arm 10 of a U-shaped bar 11 which is supported to lie above the armature shaft and parallel with it, preferably in the 110 manner shown in the drawings. The bar 11 is preferably made in two pieces for con-

venience in assembling, the two pieces being rigidly connected together, for instance by means of screws 12, in the manner shown in the drawing. The rear depending arm 13 of the bar 11 lies beyond the end wall of the motor frame and carries at its end an adjustable bearing cup 14 positioned to receive the conical rear end of the shaft 6 which also projects through the frame member.

10 The U-shaped bar 11 is supported for adjustment as a whole in parallelism with the shaft 6 by means of an adjusting screw 15 threaded in the rear bar of the motor frame and projecting through the bearing 14 in the depending arm 13 of the bar 11. The screw 15 is provided with a collar 16 intermediate its ends; and a lock nut is provided by means of which the part 13 may be clamped against the collar after the desired adjustment is obtained.

15 The motor is enclosed in the usual motor housing 17 which fits over the rim of the casing 1 and is held in place by screws threaded into the turned over ends of the front frame piece in the manner described in my co-pending application above referred to. By this arrangement the casing is readily removable to give access to the two adjusting screws 14 and 15.

20 The adjustment of the actuator 7 with relation to the anvil 8, that is, the depth of the projection of the anvil between the teeth of the actuator, determines the tone of the horn, and there is a particular point of adjustment for a particular speed of rotation at which the horn operates to best advantage. This adjustment is obtained in the first place by adjusting the screw 15 which moves the armature shaft as a whole toward and away from the anvil. As the actuator and anvil wear so that the depth of engagement becomes less, the shaft may be further adjusted toward the anvil by taking up slightly on the screw 15. By means of the 25 adjustable bearing 14 the wear in the bearings may be taken up as necessary so as to avoid any lost motion whatsoever of the armature shaft.

25 The horn is readily assembled by projecting the front part of the U-shaft bar 11 through the wall of the diaphragm casing 1 before the diaphragm is attached thereto, and then attaching it to the rear part 13. The casing 1 serves to support the bar 11 at the point the bar passes through the casing to maintain the bar in parallelism with the motor shaft, and with the ends of the bar containing the thrust bearings in alinement with the ends of the shaft.

30 My improvement is particularly designed for cooperation with the motor structure shown in my copending application mentioned above, but may obviously be used in conjunction with any type of horn motor in which the ends of the shaft are acces-

sible and sufficient clear space can be found within the casing for the bar which supports the bearings.

I claim:

1. In a warning signal the combination of 70 a diaphragm, an actuator therefor, a shaft for said actuator, a frame by which said shaft is supported and means for adjusting said actuator toward and from said diaphragm comprising an adjustable member 75 independent of said frame and engaging said shaft at both ends thereof.

2. In a warning signal the combination of 80 a diaphragm, an actuator therefor, an electric motor, said motor having a frame and an armature shaft on which said actuator is mounted, said shaft being adjustable independently of said frame, and means for adjusting said actuator toward and from said diaphragm comprising an adjustable member 85 engaging said shaft at the opposite sides of said armature.

3. In a warning signal the combination of 90 a diaphragm, an actuator therefor, a shaft for said actuator, a frame by which said shaft is supported and means for adjusting said actuator toward and from said diaphragm comprising a member mounted for adjustment in parallelism with the actuator shaft, and bearings for the opposite ends 95 of said actuator shaft carried by said member.

4. In a warning signal, the combination of 100 a diaphragm, an actuator therefor, a shaft for said actuator, a frame by which said shaft is supported, and means for adjusting said actuator toward and from said diaphragm comprising an adjustable member independent of said frame and provided with bearings engaging said shaft at 105 both ends thereof.

5. In a warning signal, the combination of 110 a diaphragm, an actuator therefor, a shaft for said actuator, a frame by which said shaft is supported, and means for adjusting said actuator toward and from said diaphragm comprising an adjustable member independent of said frame and provided with bearings 115 engaging said shaft at both ends thereof, one of said bearings being adjustable with respect to said member.

6. In a warning signal, the combination of 120 a diaphragm, an actuator therefor, a shaft for said actuator, a frame by which said shaft is supported, and means for adjusting said shaft toward and from said diaphragm comprising a member mounted for adjustment independent of said frame and thrust bearings engaging the opposite ends 125 of said actuator shaft carried by said member.

7. In a warning signal, the combination of 130 a diaphragm, an actuator therefor, a shaft for said actuator, a frame by which

said shaft is supported, rigid bearings for the opposite ends of said shaft and means independent of said frame for bodily adjusting both said bearings simultaneously in 5 parallelism with the axis of said shaft to thereby adjust said actuator toward and from said diaphragm.

8. In a warning signal, the combination of a diaphragm, an actuator therefor, a 10 shaft for said actuator, a frame by which said shaft is supported, bearings for the opposite ends of said shaft, means independent of said frame for simultaneously adjusting both said bearings in parallelism 15 with the axis of said shaft to thereby adjust said actuator toward and from said diaphragm, and means for independently adjusting one of said bearings.

9. In a warning signal, the combination 20 of a diaphragm, an actuator therefor, a shaft for said actuator, a frame by which said shaft is supported, rigid thrust bearings engaging the opposite ends of said shaft, and means for bodily adjusting both 25 said bearings simultaneously in parallelism with the axis of said shaft to thereby adjust said actuator toward and from said diaphragm.

10. In a warning signal the combination 30 of a diaphragm, an actuator for vibrating said diaphragm, an electric motor for rotating said actuator, said motor having a fixed frame, an armature shaft on which said actuator is mounted, said shaft having bearings in said motor frame, the ends of the 35 shaft projecting beyond said frame, and means for adjusting said shaft toward and from the diaphragm comprising a member supported on said motor frame for adjustment in parallelism with said motor shaft, said member having parts engaging the projecting ends of said armature shaft.

11. In a warning signal the combination 40 of a diaphragm, an actuator for vibrating said diaphragm, an electric motor for rotating said actuator, said motor having a fixed frame, an armature shaft on which said actuator is mounted, said shaft having bearings in said motor frame, the ends of 45 the shaft projecting beyond said frame, and means for adjusting said shaft toward and from the diaphragm comprising a member supported on said motor frame for adjustment in parallelism with said motor shaft, said member having parts engaging the projecting ends of said armature shaft.

50

from the diaphragm, comprising a member extending in parallelism with said armature shaft and adjacent said motor frame, said member having parts engaging the projecting ends of said armature shaft and an adjusting screw connecting said member with said motor frame whereby the adjustment of the screw shifts the member and the armature shaft bodily toward and from the 55 diaphragm.

12. In a warning signal the combination of a diaphragm, an actuator for vibrating said diaphragm, an electric motor for rotating said actuator, said motor having a fixed 60 frame, an armature shaft on which said actuator is mounted, said shaft having bearings in said motor frame, the ends of the shaft projecting beyond said frame, means for adjusting said shaft toward and from 65 the diaphragm comprising a member supported on said motor frame for adjustment in parallelism with said motor shaft, and bearings carried by said member engaging the projecting ends of said armature shaft, one 70 of said bearings being adjustable with relation to said member.

13. In a warning signal the combination of a diaphragm, an actuator for vibrating said diaphragm, a casing for said diaphragm, said casing enclosing said actuator, a motor shaft on which said actuator is mounted, said shaft projecting through said diaphragm casing and also through said actuator, a motor frame supported to the 75 rear of said diaphragm casing, said motor shaft projecting through said frame at the end opposite said diaphragm casing, and means for adjusting said motor shaft toward and from said diaphragm comprising 80 a member extending in parallelism with said motor shaft, said member being supported at one end by said diaphragm casing and at the other end by said motor frame, means for adjusting said member in parallelism 85 with said motor shaft and shaft bearings for said motor shaft carried by said member and engaging the projecting ends of said motor shaft.

100 In testimony whereof I affix my signature.

EMANUEL AUFIERO.
